UNITED STATES PATENT OFFICE

2,163,432

FILTER FOR TOBACCO SMOKING PIPES,
CIGARETTE AND CIGAR HOLDERS

John August Kostamo, New York, N. Y.

Application March 3, 1938, Serial No. 193,624

3 Claims. (Cl. 131—215)

This invention relates to new and useful improvements in a filter device for smoking pipes and cigarette and cigar holders.

More specifically, the invention proposes the construction of a receptacle or hollow member for a filter, or for aromatic material such as rum or other flavors for a smoking pipe or similar article, which is characterized by the fact that it may engage into a recess extending inward from the wall of the pipe or cigarette or cigar holder.

Still further, it is proposed to provide the receptacle or hollow member at its ends with niches in aligned positions with the smoke passage through the pipe or similar article, and to mount an absorbent element into said receptacle or hollow member to absorb the excessive oil, nicotine, dirt, etc., from the smoke, and if desired, to hold aromatic or other materials.

Still further it is proposed to construct the absorbent element of felt, cotton, paper or other similar absorbent material, and to form it with beveled sides, if desired, with the material between the sides extending into the path of the smoke to divide the smoke passage into separate branches through which the smoke will pass so that the said material may adequately remove the excess oil, nicotine, dirt, etc.

Another object of this invention is to construct a device of the class described which is simple and durable and which may be manufactured and sold at a reasonable cost.

The chief advantages gained with this invention is that the pipe may be easily cleaned and keeps clean, and the tendency for the smoke passage to become blocked is reduced.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of a smoking pipe having a filter receptacle constructed according to this invention.

Fig. 2 is a bottom view of Fig. 1.

Fig. 3 is a sectional view on the line 3—3 of Fig. 2.

Fig. 4 is a perspective view of the filter receptacle, per se, in its open position.

Fig. 5 is a sectional view of a cigarette or cigar holder constructed according to this invention.

The filter for smoking pipes, according to this

invention, comprises a smoking pipe 10 having a mouthpiece 10a and a bowl 10b. A smoke passage 11 extends through the mouthpiece and connects with the bottom end of the opening in the bowl 10b. A recess 12 extends in from one side of the pipe stem and connects with the passage 11. A receptacle or hollow member 13 having a closed outer side 13a is removably set into the recess 12. An absorbent element 14 is mounted in the receptacle or hollow member 13 and extends into the passage 11 for removing the oils, nicotine and dirt from the smoke, and for holding flavoring aromatic materials.

The receptacle or hollow member 13 may be constructed from metal or other material, and of any desired size, width, length or thickness, and is removably engaged into a tubular member 15 which is fixedly set into the recess 12. At one of its ends the tubular member 15 is formed with a lug 15a and the adjacent end of the hollow member 13 is also formed with lugs 13b. These lugs are hingedly connected together at a point 16 so that the receptacle or hollow member may be pivoted from within the tubular member when it is desired to change the absorbent elements 14. At its front end the receptacle or hollow member 13 is formed with a lip 13c and the pipe body adjacent the lip 13c is formed with a recess or niche 17 into which one's finger nail may be inserted for engaging beneath the lip 13c to pivot the hollow member 13 to its open position. The recess 12 is formed at its ends with outwardly extending portions 12a into which the lugs 13b and lip 13c extend so that the outer face 13a of the receptacle or hollow member 13 will be flush with the pipe body 10.

The filter 14 is constructed from felt, cotton or paper or other absorbent material for removing the excessive oil, nicotine and dirt from the smoke, and for holding flavoring and aromatic materials. At its top the filter 14 is formed with beveled sides 14a which extend from the edge of the hollow member 13 to divide the smoke passage 11 into branches 11a on either side of the absorbent element 14 so that the smoke will pass on either side thereof to permit the absorbent element to adequately remove the oil, nicotine and dirt.

The operation of this device is as follows:

To insert an absorbent element 14 into the receptacle or hollow member 13 one's finger nail is engaged beneath the lip 13c on the receptacle or hollow member as permitted by the niche 17, and this lip 13c is pulled outward to pivot the receptacle or hollow member with relation to the tubu-

50 55

lar element 15 to move it to its open position as shown in Fig. 4. The absorbent element 14 is then slipped into the open end of the receptacle or hollow member 13 with the beveled sides 14a extending from the top thereof. The receptacle or hollow member is then pivoted to its closed position and the beveled top portion 14a of the absorbent element 14 will extend into the smoke passage 11 dividing it into branches 11a around which the smoke will pass so that the element 14 may remove the oils, nicotine and dirt therefrom. After the absorbent element has become saturated with the foreign material it may be removed and replaced by repeating the above procedure.

15 According to the modification shown in Fig. 5 a cigarette or cigar holder 10' having a mouth-piece 10a and an opening 10c into which a cigarette or cigar may be placed is formed with a recess 12' into which the tubular member 15 and 20 the hollow member 13 extend. In other respects this form of the invention is similar to the previous form.

25 While I have illustrated and described my invention with some degree of particularity, I realize that in practice various alterations therein may be made. I therefore reserve the right and privilege of changing the form of the details of construction or otherwise altering the arrangement of the correlated parts without departing 30 from the spirit of the scope of the appended claims.

Having thus described my invention, what I claim as new and desire to secure by United States Letters Patent is:

35 1. In a smoker's article of the class described, a body portion having a passage for the smoke and a recess extended in from one side and connecting with said passage, a tubular member set into said recess with its walls engaging the walls 40 of the recess and having niches in its end walls aligned with said passage, a receptacle or hollow member for holding an absorbent element extending into said passage and formed with a

closed outer side and engaged into said tubular member with its walls engaging the walls of said tubular member and movably mounted thereon.

2. In a smoker's article of the class described, a body portion having a passage for the smoke and a recess extended in from one side and connecting with said passage, a tubular member set into said recess with its walls engaging the walls of the recess and having niches in its end walls aligned with said passage, a receptacle or hollow member for holding an absorbent element extending into said passage and formed with a closed outer side and engaged into said tubular member with its walls engaging the wall of said tubular member and movably mounted thereon, said 10 tubular member being formed at one of its ends with a lug extending at right angles to the wall thereof and disposed in a recess in said body, and said hollow member being formed at its adjacent end with a lug extending along said lug, and said 20 lugs being hingedly connected together for movably supporting said hollow member on said tubular member so that said hollow member may be removed from said tubular member when it is desired to change or remove said absorbent ele- 25

3. In a smoker's article of the class described, a body portion having a passage for the smoke and a recess extended in from one side and connecting with said passage, a tubular member set 30 into said recess with its walls engaging the walls of the recess and having niches in its end walls aligned with said passage, a receptacle or hollow member for holding an absorbent element extending into said passage and formed with a 35 closed outer side and engaged into said tubular member with its walls engaging the walls of said tubular member and movably mounted thereon, and a flange projecting from said hollow member and extending over the outer edge of said tubular 40 member.

JOHN AUGUST KOSTAMO.
